(57) **CLAIM**

I claim the ornamental design for detachable and reusable battery for smart glasses, as shown and described.

DESCRIPTION

This Non-Provisional Design Patent Application is related to U.S. Design patent application Ser. No. 29/788,643, filed contemporaneously herewith on Jul. 7, 2021, entitled “Smart Glasses with Detachable and Reusable Battery,” and U.S. Design patent application Ser. No. 29/788,645, filed contemporaneously herewith on Jul. 7, 2021, entitled “Smart Glasses without Detachable and Reusable Battery,” the entire contents of both applications of which are hereby incorporated herein by reference.

FIG. 1 is a rear, top, left perspective view of detachable and reusable battery for smart glasses, showing my new design; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; FIG. 7 is a bottom plan view thereof; and, FIG. 8 is a top, front, right perspective view thereof, shown in a state of use.

Broken lines, showing a pair of smart glasses in FIG. 8, represent environmental structure that forms no part of the claimed design. Additionally, the word “Phinge” forms no part of the claimed design and is a trademark of Phinge Corporation.
